UNITED STATES PATENT OFFICE

156,811

POTATO SLICER

Richard R. Butherus, Walla Walla, Wash., assignor of fifty per cent to Arthur Fazzari, Walla Walla, Wash.

Application August 19, 1948, Serial No. 148,187

Term of patent 3½ years

(Cl. D89—1)

To all whom it may concern:

Be it known that I, Richard R. Butherus, a citizen of the United States, residing at Walla Walla, in the county of Walla Walla and State of Washington, have invented a new, original, and ornamental Design for a Potato Slicer, of which the following is a specification, reference being had to the accompanying drawing, forming part thereof.

I claim:

The ornamental design for a potato slicer, as shown.

RICHARD R. BUTHERUS.
